US00D658713S

(12) **United States Design Patent**
Miller et al.

(10) **Patent No.:** US D658,713 S
(45) **Date of Patent:** ** May 1, 2012

(54) **INDUSTRIAL PRINTER CARTRIDGE**

(75) Inventors: **Cris R. Miller**, Champlin, MN (US);
Yanhua Li, Andover, MN (US)

(73) Assignee: **Engage Technologies Corp.**, Brooklyn Park, MN (US)

(**) Term: **14 Years**

(21) Appl. No.: **29/381,899**

(22) Filed: **Dec. 24, 2010**

(51) **LOC (9) Cl.** 18-02

(52) **U.S. Cl.** D18/56

(58) **Field of Classification Search** D18/56;
347/86-87

See application file for complete search history.
